LOUIS MASSUGER AND LÉON MARQUÉ, OF BECON LES BRUYERES, FRANCE.

HOOD LATCH.

Application filed December 24, 1921. Serial No. 524,642.

To all whom it may concern:

Be it known that we, LOUIS MASSUGER and LÉON MARQUÉ, citizens of the French Republic, residing at Becon Les Bruyeres, Department of the Seine, in France, and having P. O. address 9 Rue Watteau, in the said city, have invented certain new and useful Improvements in Hood Latches; and we do hereby declare the following to be a full, clear, and exact description of the invention, such as will enable others skilled in the art to which it appertains to make and use the same.

The present invention relates to a latch or fastener for hoods of any type, or covers in general; its object consists essentially in the provision of a very simple strong clasp or latch which, by virtue of an adjusting device which it includes will not deteriorate through use. This clasp or latch enables the hoods or covers to be rapidly locked upon their seatings with a very strong pressure, which may be varied according to requirements. This advantage is especially appreciable in the case of hoods for motor cars and like power driven vehicles, which hoods are often subject to chattering by reason of insufficient retentive pressure. Furthermore, this improved apparatus is inherently adapted for use as a lifting handle thus avoiding the necessity for applying to hoods or covers a member separately adapted for this purpose.

The accompanying Figures 1 and 2 show, by way of example, the form which is preferably given to the clasp. In these figures:

Figure 1 is a section of the clasp, the hood being closed, and

Figure 2 shows the same section, but with the hood opened.

On referring to Figure 1, it will be seen that the closing device comprises a small stirrup 2, of suitable shape, comprising, at its upper part, the rod 3 with which the hook 4 engages when the clasp is closed or locked, as will hereinafter be described. The small stirrup is fixed to the vehicle body, either by screws or by other convenient means, in such a manner that it lies within the interior of the hood or cover 1.

The member attached to the movable part of the hood 1 consists of a tubular casing 5 having an oblique base suitably attached to said hood part. The upper portion 5 of this member is bored and tapped to a certain

depth, the screw thread being left handed for example; the lower portion of the part 5 is bored to a diameter smaller than the bore of the upper part and it is traversed by the rod or hook 4, which also traverses a suitable aperture 4' cut in the hood. The shank of the hook 4 is furnished with a right-hand screw thread 6 over a certain portion of its length. A hollow cylindrical member or sleeve 7, attached at one of its ends, to an operating hand wheel 8, is screw threaded interiorly and exteriorly in suchwise as to allow it to be screwed, on the one part, onto the screw threaded shank 6 of the hook and, on the other part, into the portion 5'. The thread of this member 7 is, therefore, right-handed for the inner tapping and left-handed for the external screw threaded portion.

The operation of the closing device is very simple; the screw threaded portion of the hook 4 serves to regulate exactly the position of this hook in relation to the rod 3 of the stirrup and, when the hood is closed, in order to lock it, it suffices simply to turn the hand wheel 8 in the desired direction. In order to open it, the hand wheel 8 is turned slightly in the opposite direction. Owing to the structural arrangement employed, only a relatively very slight release of the hook 4 is required to permit of opening or closing of the hook. A small screw threaded and milled cap 9 closes the upper part 5' of the part 5. It is worthy of remark that, in the case of hoods, the device is also inherently adapted for use as a lifting handle for raising the hood. It will be seen that the exact regulation or adjustment of the position of the hook is effected by screwing up or unscrewing this latter in the hollow member 9 which moves "solid" with the controlling hand wheel. For locking purposes it is sufficient to actuate the hand wheel.

It will be apparent to any technician that any modifications in detail may be applied to the device so as to satisfy the various conditions imposed, without departing from the scope of the invention. Under certain conditions the very precise adjustment, obtained by the screw threading of the upper part of the hook, could even be dispensed with, as the adjustment could be effected simply by means of the hand wheel 8, the hook 4 being disposed in suchwise as to be able to slide without turning in the member 5, whilst the

part 7 could turn round the shank or stem of the hook whilst carrying it along at the same time.

Claims—

5. 1. A latch for automobile hoods and the like comprising a tubular casing obliquely secured to a movable part of the hood, a hook member longitudinally movable in the bore of the tubular casing and extending through 10 the adjacent hood part, a fixed element adapted to be engaged by said hook member, and a sleeve connected with the hook member and having a threaded engagement with the tubular casing so that the rotation of said 15 sleeve will move the hook member longitudinally in the tubular casing.

2. A latch for automobile hoods and the like comprising a tubular casing obliquely secured to a movable part of the hood, a hook 20 member longitudinally movable in the bore of the tubular casing and extending through the adjacent hood part, a fixed element adapted to be engaged by said hook member, and a sleeve having a threaded engagement 25 with the hook member and also having a threaded engagement with the tubular casing so that the rotation of said sleeve will

move the hook member longitudinally in the tubular casing.

3. A latch for automobile hoods and the like comprising a tubular casing secured to a movable part of the hood, a hook member longitudinally movable in the bore of the tubular casing, a fixed element adapted to be engaged by the hook member, and a sleeve 35 threaded in the tubular casing and threaded on the shank of the hook member so that rotation of the sleeve will move the hook member longitudinally in the tubular casing.

4. A latch for automobile hoods and the like comprising a tubular casing secured to a movable part of the hood, a hook member longitudinally movable in the bore of the tubular casing, a fixed element adapted to be engaged by the hook member, and a sleeve 45 threaded in the tubular casing and oppositely threaded on the shank of the hook member so that rotation of the sleeve will move the hook member longitudinally in the tubular casing.

In testimony whereof we affix our signatures.

LOUIS MASSUGER.
LÉON MARQUÉ.
